ATTORNEY

UNITED STATES PATENT OFFICE:

PETER HENRICH, OF HOQUIAM, WASHINGTON, ASSIGNOR OF ONE-HALF TO ALEXANDER POLSON, OF HOQUIAM, WASHINGTON.

BERRY-BOX.

No. 884,820.

Specification of Letters Patent.

Patented April 14, 1908.

Application filed June 24, 1907. Serial No. 380,459.

To all whom it may concern:

Be it known that I, PETER HENRICH, a citizen of the United States, residing at Hoquiam, in the county of Chehalis and State of Washington, have invented certain new and useful Improvements in Berry-Boxes, of which the following is a specification, reference being had therein to the accompanying drawings.

10 This invention relates to berry boxes; and its object is the provision of a two part box which is of simple and inexpensive construction, is capable of being quickly assembled and retained in operative condition without 15 the employment of staples, or the like, is adapted to withstand the ordinary handling encountered in shipment without becoming distorted, and through the provision of the apertures in the box shell furnishes ventilation to the contents even while in shipping cases such as are used in transportation and storage.

With these and other ends in view, the invention consists in the novel construction 25 and adaptation of devices, and the disposition and combination of the same, as will be hereinafter described and claimed.

In the drawings, Figure 1 is a vertical cross sectional view of an embodiment of my 30 invention; Fig. 2, a perspective view of the box-casing with the bottom omitted and shown partly broken away to better illustrate its construction and manner of fastening; Fig. 3, a distended view of the box-part 35 shown in Fig. 2; Fig. 4, is a view similar to Fig. 3, of the box-bottom; and Fig. 5 is a perspective view of the bottom folded into condition preparatory for inserting into the casing as shown in Fig. 2.

40 In these drawings, the reference numeral 10 represents the casing or shell of the box which, as shown in Fig. 3, is scored transversely, as at 11, in order to facilitate its being bent thereat to form the corners of the 45 box. The blank is likewise provided, adjacent of one of its ends, with an aperture 12 to receive the tongue 13 formed at the other end of the blank and such tongue is scored as at 14 whereat it is folded back upon itself, as indicated by dotted lines in Fig. 3, and lapped over the interior of the shell after the tongue has been inserted in the aforesaid aperture, as most clearly shown in Fig. 2.

Adjacent of the bottom edge 10' of the

shell the latter is provided with pairs of parallel and longitudinally arranged incisions 15, and such pairs are severally disposed to extend to each side of the respective scores 11, and thus furnish intermediate portions 16 which are thrust inwardly, as shown in Figs. 60 1 and 2, to provide bracket supports for the box bottom 17. This bottom part is formed of a rectangularly shaped blank, Fig. 4, which is transversely scored, as at 18, to make bending lines for the flaps 17', which are turned 65 upwardly, as shown in Fig. 5, and when said bottom is introduced into the shell the flaps serve to stiffen the box structure while the intermediate portion of the part 17, or the bottom proper, serves to retain the folded-over portion of said tongue in operative position and also to retain the box-shell in such condition that its corners will be rectangular.

In assembling the box, the bottom is advantageously inserted within the shell so 75 that the flaps 17' will cover the tongue, though it forms a good construction if introduced otherwise. In practice, the shell would desirably be put together at the factory as represented in Fig. 2, and then by 80 drawing either of the diagonally opposite corners together it is collapsed and made to occupy but a small space, convenient for shipment to the consumer; while the bottom parts 17 would be simply scored and shipped 85 flat, and by folding the same just before assembling the parts, the flaps 17' will have a tendency to spring outwardly and will lie snugly against the adjacent portion of the shell.

As will be noted, the forming of the supports for the bottom by protruding the shell portions 16 inwardly furnishes openings in the shell wherethrough air has free access to the underside of the box-bottom, and where 90 boxes are shipped in cases of two or more tiers, it is evident that such air will have access to the boxes in the tiers below the uppermost one and thus add greatly to the value of the boxes when employed in shipments where the contents are to be preserved in a fresh state for a relatively long time.

Having described my invention, what I claim, is—

1. A berry box consisting of a shell provided with interlocking devices and with the sides thereof slotted with the portions between the slits bent in an angular manner to

provide inwardly-extending supports integrally with and disposed at the corners of the shell, and a removable bottom mounted upon said supports and provided with upwardly-extending flaps adapted to contact with the shell.

2. A berry box consisting of a shell provided with interlocking devices and with the sides thereof slitted with the portions between the slits bent in an angular manner to provide inwardly-extending supports integral with and disposed at the corners of the shell, and a bottom mounted upon said supports.

3. As a new article of manufacture, a blank for berry boxes consisting of an elongated flat strip of material embodied by a plurality of transversely-extending scores into a plurality of sections, said strip further provided with pairs of incisions, the incisions of each pair being of equal length and extending in parallelism with respect to each other and arranged at a point slightly removed from one longitudinal edge of the strip, the

incisions of each pair projecting from each side of a score.

4. As a new article of manufacture, a blank for berry boxes consisting of an elongated flat strip of material embodied by a plurality of transversely-extending scores into a plurality of sections, said strip further provided with pairs of incisions, the incisions of each pair being of equal length and extending in parallelism with respect to each other and arranged at a point slightly removed from one longitudinal edge of the strip, the incisions of each pair projecting from each side of a score, one of said sections having a transverse slot and the other of said sections formed with a tongue extending in a direction of the length of the strip.

In testimony whereof I affix my signature in presence of two witnesses.

PETER HENRICH.
